UNITED STATES PATENT OFFICE

156,233

DESIGN FOR A CUTICLE CLIPPER OR
SIMILAR ARTICLE

August Henkel, Keene, N. H., assignor to A.
Henkel Manufacturing Corp., Keene, N. H., a
corporation of New Hampshire

Application October 28, 1948, Serial No. 149,341

Term of patent 14 years

(Cl. D86—10)

To all whom it may concern:

Be it known that I, August Henkel, a citizen of the United States and a resident of Keene, New Hampshire, have invented a new, original, and ornamental Design for Cuticle Clipper or Similar Article, of which the following is a specification, reference being had to the accompanying drawing, forming a part thereof, in which

Figure 1 is a top plan view of a cuticle clipper or similar article, showing my new design;

Fig. 2 is a side elevational view thereof; and
Fig. 3 is a front elevational view thereof.

I claim:

The ornamental design for a cuticle clipper or similar article, as shown.

AUGUST HENKEL.
